UNITED STATES PATENT OFFICE.

ABRAHAM T. GOLDFIELD, OF SPRING VALLEY, NEW YORK, ASSIGNOR TO NEW YORK CLOCK CORPORATION, A CORPORATION OF NEW YORK.

DESIGN FOR A CLOCK CASE.

Application filed July 25, 1927. Serial No. 22,879. Term of patent 7 years.

To all whom it may concern:

Be it known that I, ABRAHAM T. GOLDFIELD, a citizen of the United States of America, residing in Spring Valley, Rockland County, and State of New York, have invented a new, original, and ornamental Design for a Clock Case, of which the following is a specification, reference being had to the accompanying drawing, forming a part thereof.

In the drawing, Fig. 1 is a front view of a clock case illustrating my new design and Fig. 2 is a side view thereof on a reduced scale.

I claim:

The ornamental design for a clock case, substantially as shown.

This specification signed this 21st day of July, 1927.

ABRAHAM T. GOLDFIELD.
